OVERHEAD LOADER Herbert K. Webb, Vancouver, British Columbia,
Canada

Application October 7, 1949, Serial No. 120,050

4 Claims. (Cl. 214—131)

This invention relates to improvements in hydraulically-operated overhead loaders.

An overhead loader may be attached to any type of power traction unit, such as a bulldozer. These loaders usually consist of a bucket or scoop pivotally mounted on the traction unit in such a way that it may be lowered at one end of the unit to scoop up the material to be elevated as the unit moves in that direction. When the bucket or scoop is filled, it is raised upwardly over the traction unit so that it discharges its contents at the opposite end of the unit. The known loaders of this type are complicated, extremely heavy, and usually are made up of a large number of parts which are subject to a great deal of wear. The hydraulic apparatus for operating these loaders is usually quite complicated and it must be very strong in order to lift the great weight of the loader.

The main purpose of this invention is to provide an overhead loader which includes relatively few parts and which may be suitably braced so that the weight thereof is considerably less than the known types of equipment of this nature. This reduces the amount of power necessary to operate the loader, and a suitable leverage arrangement is employed which further reduces the required power. This arrangement makes it possible considerably to reduce the original cost of this type of equipment, and the maintenance cost is reduced by the use of fewer wearing parts.

With the above and other objects in view, the present invention consists essentially of an overhead loader for power traction units having suitable hydraulic power supply and controls, which comprises a support adapted to be mounted on each side of a power traction unit, a yoke extending from side to side of the unit pivotally mounted at its free ends on the supports, said yoke being large enough to extend around at least one end of the traction unit, a bucket carried by the yoke substantially midway between its ends, an operating arm projecting upwardly from the yoke at a pivot thereof, a pivotally mounted hydraulic cylinder extending longitudinally of the traction unit, and a ram projecting from the cylinder pivotally connected to the operating arm remote from the yoke pivot, said ram being operated by the hydraulic power supply and controls of the traction unit to raise the bucket from one end to the other of said unit, as more fully described in the following specification and illustrated in the accompanying drawings, in which:

Figure 1 is a side elevation of the overhead loader in the bucket-loading position,

Figure 2 is a similar view with the bucket in the unloading position, and

Figure 3 is a plan view of the apparatus shown in Figure 1.

Referring to the drawings, 10 is a power traction unit, shown in broken lines, of any desired type, such as a bulldozer. This unit includes the usual hydraulic power supply and controls for operating hydraulic cylinders, and

2

as these are common to this type of unit, they are not described herein.

A suitable support 14 is mounted on each side of the traction unit in any convenient manner. A yoke 15 is provided, and this yoke extends from side to side of the unit 10. The yoke is large enough to extend around at least one end of the unit when in a substantially horizontal working position, as shown in Figures 1 and 3. A bucket or scoop 16 is carried by the yoke substantially midway between its ends. This bucket may be removably or permanently mounted on the yoke. Furthermore, the bucket may even form part of the yoke. The free ends 17 of the yoke may be pivotally connected directly to the supports 14, or as preferred, inclined arms 18 may be connected to these free ends. These arms project upwardly and away from the bucket when said yoke is in its normal horizontal position, and are pivotally mounted at their free ends on pins 19 which are carried by the supports 14. Thus, the pins 19 pivotally support the yoke 15 as the arms 18 are merely extensions of the yoke. Actually, each side of the yoke 15 and the arm 18 connected thereto form a yoke arm having inclined and horizontal portions when the bucket is in its normal working position.

Suitable apparatus may be provided on each side of the traction unit for raising and lowering the bucket, but it is to be understood that, if desired, this apparatus may be provided at one side only. It is preferable to have the raising apparatus at both sides, as shown, although for the sake of clarity, the apparatus for one side only will now be described, it being understood that the apparatus at the other side of the unit is exactly the same.

An operating arm 25 projects upwardly from the yoke at the pivot pin 19 thereof. If the yoke arm 18 is used, the operating arm preferably is located approximately at right angles thereto. This positions the operating arm at a substantial angle to the vertical. A brace 26 may extend from the operating arm to the adjacent side of the yoke, and this may be substantially parallel with the inclined portion 18 of the yoke arm, as clearly shown in Figure 1. A hydraulic cylinder 30 is pivotally mounted at 31 on the support 14. This cylinder extends longitudinally of the traction unit, and it has a ram 32 projecting outwardly therefrom away from the bucket end of the yoke, and this ram is pivotally connected at 33 to the operating arm 25 remote from the pivot pin 19. When the yoke is in its normal horizontal working position, the pivot 33 is preferably located above the pivot point 31 of the hydraulic cylinder, while the latter is preferably located above the pivot points 19 of the yoke. It will be noted that the pivot point 31 is closest to the bucket end of the yoke and the pivot point 19 is the farthest away therefrom, while the pivot point 33 is between and above said pivot points.

When the yoke 15 is in its normal horizontal working position, the bucket 16 is at the ground level, and the traction unit may be moved to scoop up the material to be loaded into the bucket. The ram 32 may then be operated by the hydraulic power supply and controls of the traction unit. At this time the ram is moved outwardly from the hydraulic cylinder and this moves the operating arm 25 around the pivot 19 to raise the outer end of the yoke and its bucket. The operating arm actually acts as a lever during this operation. As the pivot point 33 travels in an arcuate path, the pivotal mounting 65 of the cylinder maintains the latter and the ram in line with said pivot point. It will be noted that during the first part of this bucket elevating movement, the ram is pushing in an upward direction. This provides a maximum amount of lift for the power available or, in other words, it reduces the amount of power necessary for this operation. When the bucket reaches a point above the

opposite end of the traction unit, it discharges and the material will drop into a vehicle or hopper which may be waiting for it, or it may be merely discharged on to the ground. Figure 2 shows the bucket in the discharge position. Although the bucket has been moved to and beyond its highest point, which is directly above the pivot point 19, one cylinder, or two, if there is a cylinder at each side of the traction unit, is used for the entire movement. This is a big advantage over most overhead loaders now in use since these require two cylinders at each side of the traction unit for a similar movement. In order to return the bucket to its loading position, it is only necessary to reverse the control apparatus to draw the ram into the cylinder. This moves the outer end of the operating arm back towards its original position, and this arm, in turn, moves the yoke and the bucket back to the loading position. It will be noted that at this time the cylinder and its ram are tangentially arranged with reference to the arcuate path followed by the pivot point 33 as the latter moves around the pivot pin 19. This makes it much easier to start the bucket into motion than would otherwise be the case.

While a scoop or bucket has been shown and described in connection with this apparatus, it is obvious that it may be removed and an ordinary blade substituted therefor, in which case the traction unit would be used as an ordinary bulldozer. The hydraulic cylinders would in this case be used to raise and lower the blade.

Various modifications may be made in this invention without departing from the spirit thereof or the scope of the claims, and, therefore, the exact forms shown are to be taken as illustrative only and not in a limiting sense, and it is desired that only such limitations shall be placed thereon as are disclosed in the prior art or are set forth in the accompanying claims.

What is claimed is:

1. An overhead loader for power traction units having traction treads on opposite sides thereof and suitable hydraulic power supply and controls, which comprises a support adapted to be mounted on each side of a power traction unit, a yoke arm pivotally mounted at one end on each support and extending towards and beyond an end of the unit, the pivots of said arms being at least as high as the top parts of the traction treads, a bucket carried by the free ends of the arms clear of the unit end, a hydraulic cylinder pivotally mounted on one of the supports and extending longitudinally of the traction unit, the pivot of the cylinder being above the yoke arm pivots and closer to the bucket than the latter, an operating arm permanently rigidly connected to and projecting upwardly from a yoke arm at the pivot thereof and extending towards the cylinder, and a ram projecting from the cylinder away from the bucket end of the yoke arms and pivotally connected to the operating arm above the cylinder pivot, said ram being operated by the hydraulic power supply and controls of the traction unit to raise the bucket from the one end of the unit to a position substantially above the opposite end thereof.

2. An overhead loader for power traction units having traction treads on opposite sides thereof and suitable hydraulic power supply and controls, which comprises a support adapted to be mounted on each side of a power traction unit, a yoke arm pivotally mounted at one end on each support and extending towards and beyond an end of the unit, the pivots of said arms being at least as high as the top parts of the traction treads, a bucket carried by the free ends of the arms clear of the unit end, an operating arm connected to and projecting upwardly from a yoke arm at the pivot thereof, said operating arm extending towards the bucket end of the yoke arms at a substantial angle to the vertical, a brace extending from the operating arm to the yoke arm to which the latter is connected, said brace being permanently rigidly connected to both of said arms, a hydraulic cylinder pivotally mounted on one of the supports and extending longitudinally of the traction unit, the pivot of

the cylinder being above the yoke arm pivots, and a ram projecting from the cylinder away from the bucket end of the yoke arms and pivotally connected to the operating arm above the cylinder pivot, said cylinder and ram being tangentially arranged with reference to the arcuate path followed by the pivotal connection of the ram with the operating arm when said connection moves around the pivot of the yoke arm, and said ram being operated by the hydraulic power supply and controls of the traction unit to raise the bucket from the one end of the unit to a position substantially above the opposite end thereof.

3. An overhead loader for power traction units having traction treads on opposite sides thereof and suitable hydraulic power supply and controls, which comprises a support adapted to be mounted on each side of a power traction unit, a yoke arm pivotally mounted at one end on each support and extending towards and beyond an end of the unit, the pivots of said arms being at least as high as the top parts of the traction treads, each yoke arm having a downwardly inclined portion from its pivot and a horizontal portion extending therefrom, a bucket carried by the free ends of the arms clear of the unit end, an operating arm permanently rigidly connected to and projecting upwardly from a yoke arm approximately at right angles to its inclined portion at the pivot thereof, a brace extending from the operating arm to the yoke arm substantially parallel with the inclined portion of the latter, a hydraulic cylinder pivotally mounted on one of the supports and extending longitudinally of the traction unit, the pivot of the cylinder being above the yoke arm pivots, and a ram projecting from the cylinder away from the bucket end of the yoke arms and pivotally connected to the operating arm above the cylinder pivot, said cylinder and ram being tangentially arranged with reference to the arcuate path followed by the pivotal connection of the ram with the operating arm when said connection moves around the pivot of the yoke arm, and said ram being operated by the hydraulic power supply and controls of the traction unit to raise the bucket from the one end of the unit to a position substantially above the opposite end thereof.

4. An overhead loader for power traction units having traction treads on opposite sides thereof and suitable hydraulic power supply and controls, which comprises a support adapted to be mounted on each side of a power traction unit, a yoke arm pivotally mounted at one end on each support and extending towards and beyond an end of the unit, the pivots of said arms being at least as high as the top parts of the traction treads, a bucket carried by the free ends of the arms clear of the unit end, a hydraulic cylinder pivotally mounted on one of the supports and extending longitudinally of the traction unit, the pivot of the cylinder being above the yoke arm pivots and closer to the bucket than the latter, an operating arm permanently rigidly connected to and projecting upwardly at a substantial angle to the vertical from the yoke arm at the pivot thereof and extending towards the cylinder, and a ram projecting from the cylinder away from the bucket end of the yoke arms and pivotally connected to the operating arm above the cylinder pivot, the pivotal connection between the ram and the operating arm being considerably closer to the bucket than the pivots of the yoke arms, said ram being operated by the hydraulic power supply and controls of the traction unit to raise the bucket from the one end of the unit to a position substantially above the opposite end thereof.
